UNITED STATES PATENT OFFICE

2,080,398

WINDER

Harry E. Cooper, Providence, R. I., assignor to
 United States Rubber Products, Inc., New
 York, N. Y., a corporation of Delaware

Application April 28, 1936, Serial No. 76,730

6 Claims. (Cl. 117—42)

This invention relates to mechanism for winding a thread or other covering strand about a core to cover the core.

Machines for winding a cover helically upon a core of elastic or inelastic filament such as rubber, wire or textile thread have been extensively used heretofore. These winding or covering machines are commonly provided with a hollow spindle through which the core to be covered may pass, and mounted upon the spindle to be rotated thereby is a spool or package containing the thread or other form of covering material that is to be wound helically upon the core as the latter is advanced through the rotating spindle.

It is important to provide a thread guide that will guide the covering thread and control its tension as this thread is unwound from its source of supply upon the rotating spindle and wound about the core. Both fliers and traveler rings and travelers have been used heretofore for this purpose.

The winding spindle is usually driven at very high speed to speed up the core covering operation, and when a traveler ring is employed that is supported in a fixed position while the spindle rotates, the traveler is pulled rapidly around the ring by the covering thread. This subjects the traveler to severe wear and necessitates its frequent renewal.

To reduce this wear it has been proposed heretofore, as disclosed in the Shorrock Patent No. 1,958,375 to provide a cap adapted to be rotated by the package supporting spindle and removably mounted upon the upper end of this spindle, and the cap is provided with one or more traveler rings and travelers which may rotate with the ring and slide thereupon. It is found, however, that due to the very high speed at which the spindle is rotated the mounting of the cap at the upper end thereof tends to increase its vibration.

The present invention therefore resides in a construction in which the traveler ring is rigidly mounted upon the support for the package of covering thread. The package support upon which the traveler ring is mounted may be the yarn supporting spool or an adapter which receives the package of thread, and in either case the ring is secured directly to a head of the spool or adapter.

The invention and novel combination of parts will be further understood from the following description when read in connection with the

accompanying drawing which illustrates good practical forms thereof.

In the drawing:

Figure 1 is a side elevation of core covering mechanism employing the construction of the present invention;

Figure 2 on a larger scale is a vertical sectional view through the adapter of Fig. 1;

Figure 3 is a bottom plan view of Fig. 2; and

Figure 4 is a side view illustrating a different application of the invention.

Referring to the drawing, 10 is an electric motor for the rotor 11 of which is mounted upon and drives the hollow spindle 12. This spindle projects from the motor a sufficient distance to receive a spool or other form of package containing the core covering thread. The core C which may be any filament to be covered, such as a rubber or textile thread or a strand of wire, is passed upwardly through the hollow spindle 12 by means not shown but well known in the art.

The core covering material T may be a thread or narrow strip of any suitable textile material or other filament. The thread T is shown in Fig. 1 as wound upon a tube 13 which may be formed of pasteboard, and this tube is mounted upon what is known as an "adapter" which is so constructed that the tube 13 can be easily mounted thereupon and removed therefrom.

The adapter shown comprises a barrel 14 and a head 15 secured to one end of the barrel, and extending lengthwise of the barrel are provided three wires 16 adapted to center the tube 13 upon the barrel and frictionally hold the tube in place thereupon. The barrel has a notch 17 at its lower end adapted to receive a driving key 18 on the spindle 12. After the tube 13 of covering thread is slipped upon the barrel 14, the adapter may be placed upon the hollow spindle 12 to be rotated thereby.

The mechanism so far described was known heretofore, and in accordance with the present invention a traveler ring 19 is secured to the adapter head 15 to rotate therewith. This constitutes an extremely simple and practical means of rotating the traveler ring, and supports it adjacent the adapter head where it is needed to guide the thread T about the head and to the point at which it is wound helically about the core C.

Various means may be employed for supporting the traveler ring 19 upon the head 15 and this is accomplished in the construction shown by providing the ring 19 with a circular flange 55

20 which fits in a recess at the inner face of the head 15 and the flange is secured to the head by the screws 21. The ring 19 may be provided with the usual traveler 22 through which the thread 5 T slides as it is unwound from the supply package and guided to the core C to provide the covering shown.

The ring 19 has an elongated construction in cross section as best shown in Fig. 2 and lies at 10 an acute angle to the supporting flange 20, but it will be apparent that the ring may be formed so that said elongated construction will extend at various other angles to the supporting flange than here shown.

15 In the modified construction of Fig. 4 the thread T is shown as wound upon a spool having the heads 23 and to one of these heads is secured the traveler ring 19.

The present construction not only provides a 20 simple and practical way of rotating the traveler ring to thereby lessen the relative travel between the ring and traveler, but by mounting the ring upon the adapter head the ring and adapter are 25 doffed together in replenishing the supply of thread upon the tube 13, which is a saving of time. Furthermore, since the adapter and ring rotate as a single unit a smooth steady guide for the thread T is provided.

30 Having thus described my invention what I claim and desire to protect by Letters Patent is:

1. A winder comprising a hollow spindle through which a filament may pass, means for rotating said spindle, a package support mounted 35 upon said spindle to rotate therewith and provided with a head at one end, a traveler ring secured to said head to be supported thereby and

to rotate therewith, and a traveler slidably mounted upon said ring.

2. A winder comprising a hollow spindle through which a filament may pass, means for 5 rotating said spindle, a package support mounted upon said spindle to rotate therewith and provided with a head, a traveler ring secured to said head to be supported thereby and to rotate therewith, and a traveler slidably mounted upon said ring and adapted to guide a thread from a 10 package upon said support about said head and wind it around said filament.

3. A winder comprising a hollow spindle through which a filament may pass, means for 15 rotating said spindle, an adapter for supporting a yarn package mounted upon said spindle to rotate therewith and provided with a head at one end, a traveler ring secured to said head to be supported thereby and to rotate therewith, and a traveler slidably mounted upon said ring. 20

4. As an article of manufacture an adapter having a hollow barrel adapted to receive a thread package and a head upon one end of said barrel, a traveler ring secured to said head to be supported thereby, and a traveler slidably upon said 25 ring.

5. As an article of manufacture an adapter having a hollow barrel adapted to receive a thread package and a head upon one end of said barrel, a traveler ring provided with a circular flange 30 for rigidly attaching the ring to said head, and a traveler slidably upon said ring.

6. As an article of manufacture a thread package support having a head, a traveler ring rigidly secured to said head, and a traveler upon 35 said ring.

HARRY E. COOPER.
